UNITED STATES PATENT OFFICE

GEORGE VARCHETTA, OF BROOKLYN, NEW YORK

BALANCED RAILROAD CROSSING GATE

Application filed September 4, 1931. Serial No. 561,167.

The invention is a railroad crossing gate which automatically closes as the train approaches and opens as the last car of the train leaves the crossing, and which is so arranged that the approaching train raises a weight that permits the gate to lower and close by gravity, and releases the weight as it leaves permitting the weight to drop and raise and open the gate.

10 The object of the invention is to provide a railroad crossing gate which automatically closes as a train approaches and opens as the train leaves.

Another object of the invention is to provide an automatic gate operating mechanism in which the gate closes and is opened by gravity.

Another object of the invention is to provide a gate operating mechanism in which both the gate and operating mechanism are balanced.

Another object of the invention is to provide a gate operating mechanism having a counter-weight on the gate, in which the counter-weight automatically adjusts its position on the gate to permit the gate to lower with ease.

A further object of the invention is to provide a railroad gate operating mechanism having a whistle in combination therewith.

And a still further object of the invention is to provide a railroad gate operating mechanism having positive mechanical movements, and which is of a simple and economical construction.

With these ends in view the invention embodies a gate having an adjustable counter-weight, an operating segment also having a counter-weight, a roller on a frame adjacent the track adapted to be engaged by a member on a train, levers adapted to raise said segment counter-weight as the roller is moved by a train, cables connecting the segment to the gate permitting the gate to lower as the segment counter-weight is raised,

a latch holding said segment counter-weight in the raised position, means releasing said latch as the last car of the train leaves the crossing, and an automatically operated signal device on said gate.

Other features and advantages of the invention will appear from the following description taken in connection with the drawings, wherein;

Figure 1 is a general outline view on a condensed scale showing the relative positions of the gate and operating devices.

Figure 2 is a general plan view also showing the relative positions of the parts.

Figure 3 is a view showing the position of the operating member on one element of a train.

Figure 4 is a detail showing the section of rail which operates the latch for raising and opening the gate as the train passes.

Figure 5 is a section thru the operating segment taken approximately on line 5—5 of Figure 6.

Figure 6 is an end elevation showing the operating segment with the holding latch housing in section.

Figure 7 is a cross section thru the operating roller mounting.

Figure 8 is a longitudinal section thru the operating roller mounting showing a side elevation of the operating segment.

Figure 9 is a plan view showing the mechanism for operating the segment counter-weight holding latch as the train passes.

Figure 10 is a section thru the mechanism shown in Figure 9 with parts broken away.

Figure 11 is a detail showing a section of rail with a guide bar in which the rail is made in sections which are normally elevated and are forced downward as the train passes over.

Figure 12 is a similar detail showing an alternate design in which the rail is solid and the operating section forced downward by the wheel flange.

Figure 13 is a view showing a compressor with a whistle and apparatus for automatically starting and stopping the same.

Figure 14 is a section thru the whistle starting mechanism.

Figure 15 is a detail showing a cross section thru the operating lever of the whistle starting mechanism.

In the drawings the device is shown as it would be made wherein numeral 1 indicates a gate, numeral 2 the operating segment, and numeral 3 a cam that operates as the last car of a train passes to release the mechanism which raises and opens the gates.

The gates 1, which may be of any design or arrangement, are positioned on both sides of the track 4 and pivotally mounted in stands 5 on pins 6 and their inner ends are provided with segments 7 having cable grooves 8 in their outer surfaces as shown. Arms 9 are also pivotally mounted in the stands 5 on pins 10 above the pins 6 and these arms are provided with slots 11 in which counter-weights 12 are held on pins 13, and at the outer ends of the arms are bolts 14 extending across the ends of the slots to clamp the sides together to hold the counter-weights in any desired position. It will be noted that the counter-weights may be positioned so that the gates will balance in any position, and as the counter-weight arms are pivoted above the gate pivots the counter-weights automatically move outward a greater distance from the center as the gates lower so that the movement of the gates will be retarded and they will lower with ease. The position of the weights may be adjusted to obtain smooth easy movement of the gates, and a projection 15 may extend from the lower corner of the segment 7 which projection may engage a stop 16 on the stand to stop or limit the movement of the gates. It will be understood that any other desired type of stop may be used and it may be positioned at any desired point or points. Other pins 17 may also extend thru the slots 11 so that additional weights 18 may be placed on them as shown in Figure 2, and these pins may be located at any desired points and adjusted as desired to obtain proper balance of the gates.

A cable 19 is attached to the segment 7 at the point 20 and this cable extends in the groove 8 and around a pulley 21 positioned at the gates, along the tracks, and over pulleys 22 and 23 to the operating segment 2 to which it is attached at the point 24. The cable may also pass around pulleys 25 and 26 to bring it close to the rail if desired.

The operating segment may be made as shown in Figures 5 and 8 with straight bars thru the center and a semi-circular member attached to the ends of the straight bars. A groove 27 is formed in the semi-circular member for the cable 19, and a weight 28 is lo-

cated at one corner which will hold the segment in the position shown in Figure 5. This segment is pivotally mounted on a pin 29 at the upper end of a stand 30 and is also held in the position shown by a counter-weight 31 which is mounted in a triangular shaped frame having arms 32 at one side, arms 33 at the other, and a cross bar 34 connecting the arms. At the ends of the arms 33 is a cross bar 35 which is engaged by a bar 36 at the ends of arms 37 and the arms 37 are integral with bars 38 which are also pivotally mounted on the pin 29, so that as the arms 38 move forward they will draw the arms 37 and also the bar 36 which will move the triangular frame of the counter-weight and raise the counter-weight. At the ends of the arms 37 are extensions 39 which have outwardly extending pins 40 that extend between bars 41 and 42 as shown in Figure 5. One end of each of the bars 41 is attached to a corresponding bar 38 and the other to a corresponding bar 42, and the other ends of the bars 42 are attached to bars 43, the opposite or lower ends of which are fixedly mounted on a shaft 44 which is rotated by a roller that is positioned in the path of a train so that as the train passing the device moves the roller, the roller will rotate the shaft 44 and move the bars 43 from the position shown in full lines in Figure 5 to the extreme position shown in dotted lines as indicated by the numeral 45. It will be noted that the bars 42 are provided with notches 46 that engage lugs 47 on the bars 43 so that as the bars 43 reach the position indicated by the dotted lines 48 the lugs 47 will raise the bars 42 to the position as indicated by the dotted lines 49. It will be noted that as the shaft 44 is rotated in a counter clockwise direction it will move the bars 43 as hereinbefore described and these bars will move the bars 42, 41, 38, and 37 to their respective dotted line positions and these will, in turn, raise the weight 31 to the positions shown in dotted lines thru the bars 36 and 35 and the triangular frame. Stops 50 are provided at the upper corners of the stands 30 to engage the bars 37 as they arrive at the final position shown by the dotted lines. Another stop 51 is provided at the top to engage and limit the upward movement of the triangular counter-weight frame. This stop 51 is pivotally mounted on the pin 29 and has extensions at the sides which are connected to springs 52 thru straps 53, blocks 54, and pins 55, so that as the members 32 of the weight frame engage the stop 51 it will give slightly and prevent a sudden stop or shock. The pins 55 are held in bearings 56 and stops 57 are provided below the bearings to limit the downward movement of the pins. These parts and frames may also be of any other design and arranged in any other manner.

The shaft 44 is rotated by a roller 58 in a frame formed by the bars 59 and 60, thru a member 61 which is fixedly mounted on the shaft 44 and which is engaged by a pin 62 mounted in the bars 59 and 60. It will be noted that as an inclined member 63 on the under side of the unit of a train, as indicated by the numeral 64 and shown in Figure 3, engages the roller 58 and moves it and the bars 59 and 60 from the dotted line position 65 to the full line position shown in Figure 8, the pin 62 will move the member 61 to the full line position shown and this member will rotate the shaft 44 and the bar 43 and raise the weight 31. At the same time the ends 66 of the pin 62 will engage projections 67 on side bars 68 and also move them to the position shown in full lines in Figure 8. The roller 58 is therefore freely mounted on the shaft 44 so that it may swing back to the dotted line position 69 when a train passes in the opposite direction or from the release cam 3 toward the crossing, and at the same time operate the device when the train passes travelling from the segment toward the crossing. A counter-weight 70 is also freely mounted upon the shaft 44 thru arms 71 and this will exert a pressure on the roller frame thru a pin 72 at the lower end and always return the roller to the upright position as soon as it is free.

At the outer ends of the side bars 68 are swivel blocks 73 which are held by pins 74, and under the blocks are springs 75 which raise the bars, roller, and other mechanism to the normal position as soon as it is released. A stop 76 is also provided to limit the downward movement of the bars 68.

A latch segment 77 is also fixedly mounted on the shaft 44 as shown in Figure 5 and a latch 78 is resiliently held against its surface by a spring 79 and when the segment is rotated by the shaft 44 a lip 80 on the segment will pass below the latch and the latch will snap outward as shown in dotted lines and the lock formed thereby will lock the segment in the dotted line position, thereby holding the shaft and other mechanism until the latch is released. On the upper side of the latch is a member 81 which has an opening 82 therein and a rod 83, having a collar 84 and a spring 85 thereon, passes thru the opening. As the latch moves to the dotted position it will move the collar and rod 83 and compress the spring 85, and when the rod 83 is drawn in the opposite direction by a cable 86 the collar will engage the member 81 and draw the latch backward and release the segment 77.

The cable 86 extends along the rail or thru a tube, as may be desired, to a pulley 87 having a gear 88 thereon and the gear 88 meshes with another gear 89 on a shaft 90, upon which the release cam 3 is mounted, as shown in Figure 9, and it will be noted that as the

cam is operated to rotate shaft 90 in a clockwise direction the gear 89 will rotate gear 88 in a counter clockwise direction and pull the cable 86 to release the latch 78. The cam 3 has a slot 91 in one side with a protruding lip 92 at the lower edge and a lug 93 at the bottom which forms a counter-weight and holds the cam in the full line position shown in Figure 10. The lug 93 may engage a stop 94 to limit the movement of the cam as shown. Above the cam is a bar 95 slidably held on rods 96 in bars 97 and resiliently held outward by springs 98 and the bars 97 are pivotally mounted on a pin 99 so that they may be moved downward, and as they are moved downward by lugs 100 the bar 95 will engage the sloping surface of the cam 3 and compress the spring until it snaps into the slot 91, and then as the lugs 100 move upward and release the bars 97 a spring 101 on a pin 102, below each of the bars will force the bars upward and raise the bar 95 which will rotate the cam until the slot 91 arrives at the dotted line position at which the bar 95 will pass out of the slot and permit the cam to return to the position shown in full lines. This operation will rotate the gears and pull the cable 86 as hereinbefore described.

The lugs 100 are mounted on sections of rails 103 as shown in Figures 1 and 10 and these sections will be forced downward by a train passing over the rails and will be held downward until the last unit of the train passes. Adjoining the sections 103 are similar sections 104 both of which are pivotally mounted at their outer ends by pins 105 and 106 to a guide bar 107 and each section is provided with a guide plate 108 which extends downward as shown to hold the sections. The abutting ends of the sections 103 and 104 are held together by a hinge 109 which is fixedly attached to one section and pivotally attached to the other. In this design the sections 103 and 104 are cut from the track rail, and it will be understood that the rail may also be solid and the sections 103 and 104 mounted on the inside as indicated by the numeral 110, shown in Figure 12, and forced downward by the wheel flanges as shown, or they may be arranged in any other manner desired. The combined length of the sections 103 and 104 should be about equal to that of the engine, a car, or any unit of the train so that the sections will remain down until the last unit of the train has passed.

A signal or alarm may also be provided at the crossing to announce the fact that a train is approaching before the gates move downward, and it will be appreciated that any suitable signal may be used and also that it may be operated in any suitable manner. In Figures 13 and 14 apparatus is shown for operating a whistle automatically by the train as the train is a considerable distance from the gate operating mechanism and shut-

ting off the whistle as it reaches the gate operating mechanism. A lever 111 is mounted some distance ahead of the segment 2 on a shaft 112 on which is a gear 113 that meshes 5 with a gear 114 on a shaft 115, and on the shaft 115 is a pulley 116 that is in line with another pulley 117 freely mounted on the shaft 112. The lever 111 is formed with two bars similar to the bars 59 and 60 shown in 10 Figures 7 and 8, and is freely mounted on the shaft 112. These bars are provided with a cross member that engages a member 118 fixedly mounted on the shaft so that as they are moved forward they will rotate the shaft 15 thru the member 118, and a similar counter-weight may also be provided to return the lever to the upright position. A cable 119 passes over pulley 117 and is attached to the pulley 116 and as the pulley is rotated it will 20 draw the cable and move a member 120 forward which will raise one end of a lever 121 and operate a whistle 122 on a compressor 123 as shown. The whistle will continue to blow until the train reaches the segment 2 25 at which time it will strike the roller 58 and rotate the shaft 44 on which is a lever 124 which is attached to a latch 125 by a cable 126 as shown in Figures 7 and 13, and as the latch, which snaps over the end of a segment 30 127 on the shaft 112 when the lever 111 is moved forward to hold the shaft and pulley, is drawn backward the cable 119 will be released and a spring 128 between the end of the member 120 and a stop 129 will return 35 the member 120 to the position shown in full lines and also return the lever 111 and the segment 127 to their respective positions as shown. It will be understood that any other type of compressor, whistle, or operating 40 mechanism may be used.

Referring again to Figure 5 it will be noted that the bars 37 and 38 may be bent outward or provided with shoulders at the points 130 and 131 so that they will clear the bars 41 and 45 42 as they operate.

A signal light 132 may also be provided adjacent the lever 111 as shown in Figure 1 and this may be controlled by contact points 133 and 134 on the stem and housing of the 50 latch 78, as shown in Figure 5, so that the contacts will close to complete a circuit thru the light to light the same as a train reaches and operates the segment 2, and the circuit will remain completed until the last unit of 55 the train passes over and operates the cam 3, at which time the latch will be withdrawn and the circuit broken. This will provide a signal to a train following to warn the train that another train is at the crossing.

60 The train unit to which the bar 63 is attached as shown in Figure 3 is shown as a car; however, it will be understood that this bar may be mounted on the engine or any other unit of the train or upon any other 65 vehicle.

It will be understood that other changes may be made in the construction without departing from the spirit of the invention. One of which changes may be in the use of a gate of any other type or description or of any combination of gates, another may be in the shape or design of the operating segment, another may be in the use of other means for raising the counter-weight independent of the operating segment, another may be in the use of other means for releasing the segment holding latch, and still another may be in the use of other means for connecting the various parts so that their operation will be coordinated and automatic.

The construction will be readily understood from the foregoing description. In use the apparatus may be installed as shown and described and it will be noted that as a train approaches it will first engage the lever 111 which will start the whistle blowing and the whistle will continue to blow until the train engages the roller 58 when it will release the whistle operating mechanism, and at the same time raise the counter-weight 31 which will release the operating segment 2 and permit the gates to lower. The weight 31 will be held in this position by the latch 78 so that the gates will remain lowered until the last unit of the train passes over the sections of rails operating the cam 3 at which time these sections will raise and permit the cam to operate to release the latch 78 and this will release a weight 31 which will exert a pressure on one end of the segment 2 sufficient to return the segment to the position shown in full lines in Figure 1 and at the same time raise the gates. It will be understood that the essential feature of this invention is in the balancing of the operating segment and the gates and it will be noted that the weights may be positioned, adjusted and regulated so that the parts will operate with a smooth easy movement. In the design as shown, with the weight 31 raised and the segment free, the segment and gates will come to rest with the gates lowered and the segment in the position shown in Figure 8, and when the weight 31 is applied it will overbalance the segment and raise the gates.

Having thus fully described the invention what I claim as new and desire to secure by Letters Patent, is:—

1. In an automatically operated railroad crossing gates, gates at the crossing, a whistle at the crossing, gate operating mechanism positioned ahead of the crossing, whistle operating mechanism positioned ahead of the gate operating mechanism, a train, means on said train for operating said whistle operating mechanism to blow the whistle and for operating said gate operating mechanism to lower the gates and silence the whistle, locking means holding said gate operating mechanism with the gates lowered, and means re-

- leasing said locking means as the train leaves the crossing, said operating mechanism operating to raise the gates as the locking means is released.
- 5 2. In a gate operating device, in combination, gates, a gate operating segment, adjustable counter-weights on said gates, other adjustable counterweights on said segment, means connecting said gates and segment, 70
10 said gates and segment adapted to balance in the free position with the gates closed, an independent weight adapted to act on said segment to raise said gates, means raising said independent weight to release the segment as a train approaches, and means releasing said weight allowing it to act on said segment to raise the gates as the train leaves. 75
- 15 3. In combination, a balanced railroad crossing gate, means automatically adjusting the balancing parts of said gate to retard the movement thereof as the gate approaches the horizontal position, a balanced member cooperating with said gate, a weight adapted to be applied to said balanced member to raise said gate, a train, means operated by said train for relieving said balanced member of said weight, and means adapted to operate after the train leaves the crossing to apply said weight to said balanced member. 80
- 20 25 4. In combination, a railroad crossing gate, a counter-weight slidable on said gate, means for manually adjusting the position of said counter-weight to balance said gate, a balanced member cooperating with said gate, a weight adapted to be applied to said balanced member to raise said gate, a train, means operated by said train for relieving said balanced member of said weight, and means adapted to operate after the train leaves the crossing to apply said weight to said balanced member. 85
- 30 35 5. In combination, a railroad crossing gate, a counter-weight slidable on said gate, mounting means for said counter-weight whereby it will move to a greater distance from the center to retard the movement of said gate as it approaches the horizontal position, a balanced member cooperating with said gate, a weight adapted to be applied to said balanced member to raise said gate, a train, means operated by said train for relieving said balanced member of said weight, and means adapted to operate after the train leaves the crossing to apply said weight to said balanced member. 90
- 40 45 6. In combination, a balanced railroad crossing gate, a balanced member cooperating with said gate, means for adjusting the balancing parts of said balanced member, a weight adapted to be applied to said balanced member to raise said gate, a train, means operated by said train for relieving said balanced member of said weight, and means adapted to operate after the train leaves the crossing to apply said weight to said balanced member to raise the gate. 95
- 50 55 7. In combination, a balanced gate, a balanced member cooperating with said gate, a weight adapted to act upon said balanced member to raise said gate, means for adjusting said weight, means for raising said weight and supporting it above said balanced member, and means for releasing said weight. 100
- 60 65 8. In combination, a balanced railroad crossing gate, a balanced member cooperating with said gate, a weight adapted to be applied to said balanced member to raise said gate, a track, a train, an inclined member on the train, a member in said track adapted to be engaged by said inclined member, said track member adapted to relieve said balanced member of said weight as it is engaged by said inclined member, and means adapted to operate after the train leaves the crossing to apply said weight to said balanced member to raise the gate. 105
- 70 75 9. In combination, a balanced railroad crossing gate, a balanced member cooperating with said gate, a weight adapted to act upon said balanced member to raise said gate, a track, a train, an operating member on said train, a member in said track positioned to be engaged by said operating member, means connecting said track member to said weight thru which the weight will be raised to relieve said balanced member as the track member is engaged by said operating member, means locking said connecting means with the weight raised, and means for releasing said locking means. 110
- 80 85 10. In combination, a balanced railroad crossing gate, a balanced member cooperating with said gate, a weight adapted to act upon said balanced member to raise said gate, a track, a train, an operating member on said train, a member in said track positioned to be engaged by said operating member, means connecting said track member to said weight thru which the weight will be raised to relieve said balanced member as the track member is engaged by said operating member, means locking said connecting means with the weight raised, releasing mechanism for said locking means positioned beyond the crossing, and means for operating said releasing mechanism after the last unit of the train leaves the crossing. 115
- 90 95 11. In combination, a balanced gate, a balanced member cooperating with said gate, a weight adapted to act upon said balanced member to raise said gate, means for raising said balanced member as the gate lowers, means for raising said weight above said balanced member allowing it to raise, means for releasing said weight, a whistle, means for blowing said whistle before said weight is raised, and means for stopping said whistle as the weight is raised. 120
- 100 105 12. In combination, a balanced railroad crossing gate, a balanced member cooperating with said gate, a weight adapted to act upon said balanced member to raise said gate, a track, a train, an operating member on said train, a member in said track positioned to be engaged by said operating member, means connecting said track member to said weight thru which the weight will be raised to relieve said balanced member as the track member is engaged by said operating member, means locking said connecting means with the weight raised, releasing mechanism for said locking means positioned beyond the crossing, and means for operating said releasing mechanism after the last unit of the train leaves the crossing. 125
- 110 115 130

crossing gate, a balanced member cooperating with said gate, a weight adapted to be applied to said balanced member to raise said gate, a train, means operated by said train for relieving said balanced member of said weight, means adapted to operate after the train leaves the crossing to apply said weight to said balanced member, means for sounding an alarm before the train operates the said relieving means, and means for stopping the alarm as the train operates the relieving means.

In testimony whereof I affix my signature.

GEORGE VARCHETTA.
